United States Patent Office

Des. 188,185
Patented June 14, 1960

188,185

STADIUM CHAIR

Bror W. Henrikson, Alfred C. Hoven, William S. Lindberg, and Walter E. Nordmark, all of Grand Rapids, Mich., assignors to American Seating Company, Grand Rapids, Mich., a corporation of New Jersey

Filed May 11, 1959, Ser. No. 55,871

Term of patent 14 years

(Cl. D15—8)

Fig. 1

Figure 1 is a front and side perspective view of a stadium chair showing our new design, the chair seat being here shown in an upwardly swung position.

Figure 2 is a perspective view of the chair similar to Figure 1 and showing the chair seat in a lowered position for occupancy; and

We claim:

The ornamental design for a stadium chair, substantially as shown.
